UNITED STATES PATENT OFFICE

1,940,524

FUEL PUMP

Louis Henri Libert Bellem, Asnières, and Erling Christian Foss, Neuilly-sur-Seine, France

Application January 9, 1932, Serial No. 585,782,
and in France January 9, 1931

18 Claims. (Cl. 103—37)

The present invention relates to fuel pumps having an adjustable output, of the kind comprising a piston moving in a cylinder, and a movable member, which can moreover be the cylinder itself, the piston having a reciprocating movement, during the discharge stroke of which, at a given variable moment the movement of the displaceable member is controlled, said displaceable member by cooperating with a distribution opening, enabling the fuel to be discharged.

The pump according to the invention is broadly characterized by the fact that during the suction stroke, the movable member is maintained in its suction position by the piston itself which likewise controls the movement of said member towards its discharge position, said piston including, to this end, a nose acting on the movable member in the opposite direction to that in which acts the spring which is then held in a sort of cage formed by the piston and its nose and the cylinder.

In one embodiment of the invention, the controlling nose of the piston not only holds the movable member in its suction position but likewise brings it into this position during the suction stroke, while according to another embodiment the movable member is brought into the suction position by external members, for example, by an arm rotating with the motor shaft and carrying balls controlled by a cam and adapted to depress the movable member at suitable adjustable periods.

Other features and peculiarities of the invention will become apparent from the ensuing description taken in conjunction with the accompanying drawings wherein:

Fig. 1 is a longitudinal section through a double pump according to the invention.

Fig. 2 shows a multiple pump.

Fig. 3 shows a constructional modification of the delivery adjusting device.

Fig. 4 shows a modified pump with fixed cylinder.

Fig. 5 illustrates, in longitudinal elevation, a multiple pump according to a modification.

Fig. 6 is a plan view of a detail of a member of the pump of Fig. 5.

The double pump shown in Fig. 1 comprises essentially a body portion 1 at the upper part of which is provided a reservoir 2 into which the fuel is fed by a piping 3. Said reservoir 2 has a discharge orifice 4 against which the upper end of the displaceable cylinder 5 of the pump can press, in which cylinder moves a piston 7 having an extension piece 18 which screws into a sleeve

8 driven by a cam shaft 9 through the instrumentality for example of a roller 10. Between a flange 14 provided at the lower end of the cylinder 5 and said extension piece 18 of the piston 7 is interposed a fairly powerful spring 12. On the extension piece screws a sleeve 19 on which is mounted a pinion 20 adapted to engage with a rack 23. At its upper end, the sleeve 19 is formed with a nose 22 adapted to act on the flange 14 of the cylinder 5.

The device operates in the following manner:

At the upper dead centre (right-hand pump of Fig. 1), the cylinder 5 is pressed against the orifice 4, and the spring 12 is compressed between the extension piece 18 of the piston 7 and the flange 14 of the cylinder 5.

There is a certain play a between the nose 22 of the sleeve 19 and the flange 14 of the cylinder 5.

At the beginning of the down stroke, the piston 7 and its sleeve 19 descend alone until the nose 22 engages with the flange 14, that is to say after taking up the play a . At this instant, with the piston 7 continuing to descend, said nose 22 displaces the cylinder 5 which also descends. At the beginning of the up-stroke, all the members move simultaneously until the cylinder 5 presses against the orifice 4. At this instant, the piston 7 and its sleeve 19 continue to rise a distance equal to the play a , the cylinder remaining stationary. During said stroke a , the piston 7 discharges fuel through the orifice 4. It is obvious that the delivery of said discharge depends on the extent of the play a , which can be varied by displacing the rack 23 to rotate the pinion 20 and thereby screw the extension piece 18 more or less into the sleeve 8.

The two pistons can be driven alternately in any known manner, by a single cam shaft 9. The down stroke of each of said pumps can be controlled by means of a tappet 24 which is advantageously arranged between said two pumps, said tappet being rocked on each up-stroke of one of the pumps, and thereby effecting the down-stroke of the other pump.

A multiple pump (6 units) has been shown in Fig. 2. Said pumps are arranged on a circumference, thereby enabling them to be driven by means of a single cam 25 provided on a horizontal cam plate 26. Tappets, such as 24, are interposed between said pumps. The simultaneous adjustment of the output of all said pumps can be ensured by a central pinion 27 meshing with all the pinions 20. Said pinion 27 can itself be driven from the outside by any means, automatic

or not, thereby enabling the speed of the motor to be very readily varied.

In the modification of Fig. 3 the piston 7 does not screw through the medium of its extension piece 18, in the sleeve 8. On the contrary, the extension piece 18 is suppressed and the piston is mounted directly on the member 8, the sleeve 19 then screwing on said member 8. The present invention applies not only to pumps of the type 10 illustrated in Figs. 1 to 3 where the cylinder is movable, but also to pumps having a fixed cylinder, as shown in Fig. 4, surrounded by a timing sleeve 16. In this case, said sleeve 16 operates in exactly the same conditions as the cylinder 5 of Figs. 1 to 3, that is to say that according to the setting of the piston 7 relative to the sleeve 8, it covers, sooner or later, during the up-stroke, orifice 67 formed in the wall of the cylinder 5.

Finally, in the modification shown in Figs. 5 20 and 6, the adjustment of the output is obtained by means of an arm 30 keyed to the drive shaft 9 and at the end of which are lodged two balls 31 which move between a raceway 32 and a plate 33. Said plate 33 has for each of the pumps a cam 34, while the raceway 32 has a corresponding number of slots each of which receives a collar 35 slidably mounted on a corresponding cylinder so as to move up and down in its associated slot. When the upper ball 31 passes 30 under a shoulder 34 it is depressed thereby and the lower ball which is then passing over one of the collars 35, depresses the latter which in its turn forces its associated cylinder 5 to descend.

It is then obvious that by adjusting the angular 35 position of the cam 34 the instant will be varied at which, during the discharge stroke of the piston 7 of the corresponding pump, the cylinder 5 will be forced down, and disengaged from the discharge orifice, thereby stopping said discharge. 40 To adjust the angular position of the cam 34, the plate 33 is keyed to the end of a shaft 37, the angular displacement of which can be controlled from without either by hand or automatically. With this arrangement, either the end or the beginning 45 of the discharge of each pump can therefore be varied.

As in the case of Fig. 2, the upward movement of the various pistons is controlled by a single cam plate 26, but in this case the downward movement is controlled by a second cam plate 40.

It is, of course, obvious that the invention has only been described and illustrated herein in a purely explanatory but in no way limitative manner, and that it could be subjected to any modifications of detail without departing from the spirit thereof.

We claim:

1. In a fluid discharging pump, the combination 50 of a reservoir containing liquid, a hollow member open at both ends and displaceable in said reservoir, a piston located within said member, means for reciprocating said piston, a discharge pipe leading from said pump, spring means 55 mounted between said piston and a flange on said member and causing said member to move with the piston during the first portion of the piston discharge stroke, fixed means with which said member cooperates to cut off communication between said reservoir and the space within said member above said piston after predetermined displacement of said member during the discharge stroke of said piston, said piston then discharging liquid into said discharge pipe, and means secured to said piston and adapted to contact with said member after predetermined downward displacement of said piston.

said piston to hold said member in the suction position.

2. In a fluid discharging pump, the combination 80 of a reservoir containing liquid, a hollow member open at both ends and displaceable in said reservoir, a piston located within said member, means for reciprocating said piston, a discharge pipe leading from said pump, spring means 85 mounted between said piston and a flange on said member and causing said member to move with the piston during the first portion of the piston discharge stroke, fixed means with which said member co-operates to cut off communication between said reservoir and the space within said member above said piston after predetermined displacement of said member during the discharge stroke of said piston, said piston then discharging liquid into said discharge pipe, means secured to said piston and adapted to contact with said member after predetermined downward displacement of said piston to hold said member in the suction position, and means for 90 adjusting the position of said last mentioned means relatively to said piston.

3. In a fluid discharging pump, the combination 95 of a reservoir containing liquid, a hollow member open at both ends and displaceable in said reservoir, a piston located within said member, means for reciprocating said piston, a discharge pipe leading from said pump, spring 100 means mounted between said piston and a flange on said member and causing said member to move with the piston during the first portion of the piston discharge stroke, fixed means with which said member co-operates to cut off communication between said reservoir and the space within said member above said piston after predetermined displacement of said member during the discharge stroke of said piston, said piston then discharging liquid into said discharge pipe, and a housing for said spring means secured to said piston and having a projecting nose adapted to contact with said member after predetermined downward displacement of said piston to hold said member in the suction position.

4. A pump as described in claim 3, including 110 means for adjusting the relative positions of said piston and member independently of the relative movements of said piston and member during normal operation.

5. In a fluid discharging pump, the combination 115 of a reservoir containing liquid, a hollow member open at both ends and displaceable in said reservoir, a piston located within said member, means for reciprocating said piston, a discharge pipe leading from said pump, spring means 120 mounted between said piston and a flange on said member and causing said member to move with the piston during the first portion of the piston discharge stroke, fixed means with which said member co-operates to cut off communication between said reservoir and the space within said member above said piston after predetermined displacement of said member during the discharge stroke of said piston, said piston then discharging liquid into said discharge pipe, a housing for said spring, means for connecting said housing to said piston, said housing including a nose adapted to contact with the flange of said member after predetermined downward displacement of said piston to hold said member in the suction position, and means for displacing said housing relatively to said piston.

6. In a fluid discharging pump, the combination 125 of a reservoir containing liquid, a hollow

- member open at both ends and displaceable in said reservoir, a piston located within said member, means for reciprocating said piston, a discharge pipe leading from said pump, spring means mounted between said piston and a flange on said member and causing said member to move with the piston during the first portion of the piston discharge stroke, fixed means with which said member co-operates to cut off communication between said reservoir and the space within said member above said piston after predetermined displacement of said member during the discharge stroke of said piston, said piston then discharging liquid into said discharge pipe, a housing for said spring including a portion secured to said piston, a sleeve coupling said piston reciprocating means to said portion of said housing secured to said piston, said portion screwing in said sleeve, said housing having a nose adapted to engage with the flange of said member on the downward stroke of said piston to depress said member, and means for screwing said housing into and out of said sleeve.
7. In a fluid discharging pump, the combination of a cylinder plunging in the liquid to be pumped, a discharge pipe in alignment with the axis of said cylinder, said cylinder being displaceable into and out of contact with the edge of the orifice of said discharge pipe, a piston mounted in said cylinder, means for reciprocating said piston, said piston discharging fluid through said discharge orifice when said cylinder contacts with the edge of said orifice, spring means interposed between flanges on said piston and cylinder respectively and tending to maintain said cylinder in contact with the edge of said orifice, means mounted on said piston and adapted to contact with said cylinder flange after predetermined downward displacement of said piston to hold said cylinder in the suction position, and means for varying the relative positions of said piston and cylinder independently of the relative movements of said piston and cylinder during normal operation.
8. In a fluid discharging pump, the combination of a cylinder plunging in the liquid to be pumped, a discharge pipe in alignment with the axis of said cylinder, said cylinder being displaceable into and out of contact with the edge of the orifice of said discharge pipe, a piston mounted in said cylinder, means for reciprocating said piston, said piston discharging fluid through said discharge orifice when said cylinder contacts with the edge of said orifice, a housing for said spring means mounted on said piston and having a projecting nose adapted to contact with the flange of said cylinder after predetermined downward displacement of said piston to depress said cylinder, and means for adjusting the position of said housing relative to said cylinder to vary the instant of engagement of said housing nose with said cylinder flange with respect to the suction stroke of said piston.
9. In a fluid discharging multiple pump, the combination of a reservoir containing liquid, a plurality of hollow members open at both ends and displaceable in said reservoir, a plurality of discharge pipes leading from said pump, pistons located within said members, a drive shaft, a plate mounted on said drive shaft and having a single cam, means associated with each piston and actuated in turn by said cam for displacing the corresponding piston on its discharge stroke, a spring mounted between each piston and a flange on the associated member and causing said member to move with the piston during the first portion of the piston discharge stroke, means driven by said drive shaft for displacing said piston on its suction stroke, and a plurality of fixed means with which said members co-operate respectively to cut off communication between said reservoir and the space within each member above its piston after predetermined displacement of said member during the discharge stroke of said piston, said piston then discharging liquid into said discharge pipe, a vertically displaceable device rotated from said drive shaft past each of said members in turn, a plate including as many cams as there are members adapted to project into the path of rotation of said vertically displaceable device and thereby depress the latter, and means associated with each member and acted on by said device in its downward displacement for displacing downwardly the corresponding member.
10. In a fluid discharging multiple pump, the combination of a reservoir containing liquid, a plurality of hollow members open at both ends and displaceable in said reservoir, a plurality of discharge pipes leading from said pump, pistons located within said members, a drive shaft, a plate mounted on said drive shaft and having a single cam, means associated with each piston and actuated in turn by said cam for displacing the corresponding piston on its discharge stroke, a spring mounted between each piston and a flange on the associated member and causing said member to move with the piston during the first portion of the piston discharge stroke, means driven by said drive shaft for displacing said piston on its suction stroke, and a plurality of fixed means with which said members co-operate respectively to cut off communication between said reservoir and the space within each member above its piston after predetermined displacement of said member during the discharge stroke of said piston, said piston then discharging liquid into said discharge pipe.
11. In a fluid discharging multiple pump, the combination of a reservoir containing liquid, a plurality of hollow members open at both ends and displaceable in said reservoir, a plurality of discharge pipes leading from said pump, pistons located within said members, a drive shaft, a plate mounted on said drive shaft and having a single cam, means associated with each piston and actuated in turn by said cam for displacing the corresponding piston on its discharge stroke, a spring mounted between each piston and a flange on the associated member and causing said member to move with the piston during the first portion of the piston discharge stroke, means driven by said drive shaft for displacing said piston on its suction stroke, a plurality of fixed means with which said members co-operate respectively to cut off communication between said reservoir and the space within each member above its piston, means rotated by said drive shaft for depressing each member in turn against its associated spring, and means for adjusting the instant of operation of said member depressing means relatively to the operation of said piston displacing cam.
12. A pump as described in claim 11, including means for adjusting the angular position of the multi-cam plate.
13. In a fluid discharging multiple pump, the

- combination of a reservoir containing liquid, a plurality of hollow members open at both ends and displaceable in said reservoir, a plurality of discharge pipes leading from said pump, pistons located within said members, a drive shaft, a plate mounted on said drive shaft and having a single cam, means associated with each piston and actuated in turn by said cam for displacing the corresponding piston on its discharge stroke, a spring mounted between each piston and a flange on the associated member and causing said member to move with the piston during the first portion of the piston discharge stroke, means driven by said drive shaft for displacing said piston on its suction stroke, a plurality of fixed means with which said members co-operate respectively to cut off communication between said reservoir and the space within each member above its piston after predetermined displacement of said member during the discharge stroke of said piston, said piston then discharging liquid into said discharge pipe, an arm mounted on said driving shaft, a vertically displaceable device carried by said arm, a plate formed with as many cams as there are members adapted to project into the path of rotation of said displaceable device and thereby depress the latter, collars mounted on said members and adapted to be depressed by said displaceable device under the action of said cams and thereby move the corresponding members downwardly, and means for varying the angular position of said multi-cam plate.

14. In a fluid discharging multiple pump, the combination of a reservoir containing liquid, a plurality of hollow members open at both ends and displaceable in said reservoir, a plurality of discharge pipes leading from said pump, pistons located within said members, a drive shaft, a plate mounted on said drive shaft and having a single cam, means associated with each piston and actuated in turn by said cam for displacing the corresponding piston on its discharge stroke, a spring mounted between each piston and a flange on the associated member and causing said member to move with the piston during the first portion of the piston discharge stroke, means driven by said drive shaft for displacing said piston on its suction stroke, a plurality of fixed means with which said members co-operate respectively to cut off communication between said reservoir and the space within each member above its piston after predetermined displacement of said member during the discharge stroke of said piston, said piston then discharging liquid into said discharge pipe, an arm mounted on said driving shaft, a plate formed with as many cams as there are members, a race-way, a vertically displaceable device carried by said arm and moving between said multi-cam plate and said race-way, collars mounted on said members and adapted to move up and down in slots formed in said race-way, said vertically displaceable device depressing said members through the medium of said collars when passing over said cams, and means for varying the angular position of said multi-cam plate.

15. In a fluid discharging multiple pump, the combination of a plurality of cylinders plunging in the liquid to be pumped, a plurality of discharge pipes in alignment respectively with the axes of said cylinders, said cylinders being displaceable into and out of contact with the edges of the orifices of the corresponding discharge

5 pipes, pistons located in said cylinders, a drive shaft, a plate mounted on said drive shaft and having a single cam, means associated with each piston and actuated in turn by said cam for displacing the corresponding piston on its discharge stroke, a spring mounted between each piston and its associated cylinder and tending to force said cylinder against the edge of the corresponding orifice, means secured to each piston and adapted to contact with the corresponding cylinder after predetermined displacement of the piston, to move the cylinder into its suction position and a second plate provided with a single cam and mounted on said drive shaft, said second cam displacing each piston in turn in the opposite direction to said first cam.

10 16. In a fluid discharging multiple pump, the combination of a plurality of cylinders plunging in the liquid to be pumped, a plurality of discharge pipes in alignment respectively with the axes of said cylinders, said cylinders being displaceable into and out of contact with the edges of the orifices of the corresponding discharge pipes, pistons located in said cylinders, a drive shaft, a plate mounted on said drive shaft and having a single cam, means associated with each piston and actuated in turn by said cam for displacing the corresponding piston on its discharge stroke, a spring mounted between each piston and its associated cylinder and tending to force said cylinder against the edge of the corresponding orifice, a vertically displaceable member rotated from said drive shaft past each of said cylinders in turn, a plate including as many cams as there are cylinders adapted to project into the path of rotation of said vertically displaceable member and thereby depress the latter, and means associated with each cylinder and acted on by said member in its downward displacement for displacing downwardly the corresponding cylinder.

15 17. A pump as described in claim 16, including means for adjusting the angular position of the multi-cam plate.

20 18. In a fluid discharging multiple pump, the combination of a plurality of cylinders plunging in the liquid to be pumped, a plurality of discharge pipes in alignment respectively with the axes of said cylinders, said cylinders being displaceable into and out of contact with the edges of the orifices of the corresponding discharge pipes, pistons located in said cylinders, a drive shaft, a plate mounted on said drive shaft and having a single cam, means associated with each piston and actuated in turn by said cam for displacing the corresponding piston on its discharge stroke, a spring mounted between each piston and its associated cylinder and tending to force said cylinder against the edge of the corresponding orifice, an arm mounted on said driving shaft, a vertically displaceable member carried by said arm, a plate formed with as many cams as there are cylinders adapted to project into the path of rotation of said displaceable member and thereby depress the latter, collars mounted on said cylinders and adapted to be depressed by said displaceable member under the action of said cams and thereby move the corresponding cylinders downwardly, and means for varying the angular position of said multi-cam plate.
